(57) **CLAIM**

The ornamental design for a case for cleaner, as shown and described.

DESCRIPTION

FIG. 1 is an upper front perspective view of a case for cleaner, showing our new design;

FIG. 2 is a front elevation view thereof, the rear elevation view being a mirror image thereof;

FIG. 3 is a top view thereof;

FIG. 4 is a bottom view thereof;

FIG. 5 is a right side elevation view thereof, the left side elevation view being a mirror image thereof; and,

FIG. 6 is an upper front perspective view thereof in its intended environment.

The portions of the case for cleaner shown in broken lines form no part of the claimed design.

The broken line showings of FIG. 6 of a cleaner and a handle are for the purpose of illustrating environmental structure and form no part of the claimed design.
